Primary Examiner — Michael C Stout*Assistant Examiner* — Fitzgerald L Butac(74) *Attorney, Agent, or Firm* — GTC Law Group PC & Affiliates(57) **CLAIM**

The ornamental design for a robot comprising a service module, as shown and described.

DESCRIPTION

FIG. 1 is a side elevation view of a robot comprising a service module, showing our new design;

FIG. 2 is a front side elevation view thereof; and,

FIG. 3 is a front perspective view thereof.

The broken lines show portions of a robot and service module which form no part of the claimed design.
